C. L. GOODRUM,
TELEPHONE EXCHANGE SYSTEM,
APPLICATION FILED DEC. 12, 1914.

Patented Oct. 17, 1916.

UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,201,455.

Specification of Letters Patent. Patented Oct. 17, 1916.

Application filed December 12, 1914. Serial No. 876,838.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

10 This invention relates to a telephone exchange system, and its object is to provide means by which, when a subscriber's telephone number is changed, connection with his telephone can be secured by calling either the old or the new number.

15 While the invention is applicable in general to a change in a subscriber's telephone number, it is especially applicable where there is also a change in the kind of service.

20 With the above object in view, and in accordance with the invention, a special switch is connected to the connector multiple terminals of the old number and operates, when connection is made to those terminals, to 25 automatically extend the connection to the new line. In case there is no change in the kind of service, the special switch would merely step to a terminal to which the new line is connected. In case there is a change 30 in the kind of service, as, for example, from an individual line to private branch exchange trunks, the special switch, which is connected to the connector multiple terminals of the old number, operates, when connection is made to those terminals, to 35 test over and hunt for an idle one of the private branch exchange trunks. The private branch exchange trunks or the new line, as the case may be, are also connected to their 40 proper new number terminals on the connectors, so that service is secured either by calling the new or the old number.

45 As an additional feature of the invention, a message register may be provided for counting the calls that come through the old number terminals, the purpose being to keep the special switch in that particular service only until the other subscribers become familiar with the new number, which fact is 50 disclosed by the message register.

55 The invention may be more readily understood by reference to the accompanying

drawing, showing an arrangement of circuits and apparatus embodying the invention.

55

In the drawings, the subscriber's telephone station A is shown as served by a plurality of private branch exchange trunks 1, 2, 3. At the main office these trunks are connected to the multiple terminals of a trunk hunting connector B. It is assumed that the subscriber formerly was served by an individual line connected to multiple terminals on a connector C, and that the service having been changed from an individual line to 60 private branch exchange service, a new number is given to the subscriber's station. In order that the subscriber may be readily reached even if the old number is called, the multiple terminals to which his individual line was formerly connected are now 65 connected to a trunk-hunting switch D, to the terminals of which the private branch exchange trunks 1, 2, 3, are also connected. Therefore when a calling line is connected 70 to the terminals of the connector C, the trunk-hunting switch D hunts for an idle trunk leading to the subscriber's station A.

75 The apparatus may be of any suitable construction, that indicated in the drawing being of well-known type and hence shown in 80 a conventional manner.

85 The operation of the system is as follows: In case a call is made for the subscriber at station A and the call is for his new number the trunk-hunting connector B connects the calling subscriber with the private branch exchange of the wanted subscriber in the usual manner. If, however, the call 90 is made for the old instead of the new number, the calling subscriber's line is extended in the usual manner to the multiple terminals 4, 5 of the connector C to which the wanted subscriber's line was formerly directly connected. Thereupon a circuit is 95 closed over the local third wire for the relay 6, which being actuated opens its back contact 7 and closes its front contact 8, thereby closing a circuit for a relay 9 as follows: from grounded battery, through one winding of relay 9, normal contact 10, closed in the initial position of switch D, contact 8 to ground. Relay 9 being thereby actuated 100 closes a locking circuit for itself as follows:

from grounded battery, through the other winding of relay 9, front contact 11 of relay 9, side switch 12 and brush 13 of switch D, to ground. Relay 9 controls, at its front 5 contact 14, a circuit for the motor magnet 15 and the escape magnet 16 of switch D. The motor magnet 15 interrupts its own circuit at contact 17, thereby advancing the brushes 13, 18 and 19 of switch D, step by 10 step until they find an idle trunk. When an idle trunk is thus found, ground being removed from brush 13, the relay 9 is de-energized, and the circuit for the motor magnet 15 and the escape magnet 16 is 15 opened at contact 14. The brushes of the special switch D therefore stop upon the terminals of the idle trunk, and the escape magnet 16 causes the side switches 20, 21 and 12 to move to their second position. In 20 such position the brush 13 connects the brush 13 to ground, thereby making the selected trunk busy. The brushes 20 and 21 connect the calling line to the brushes 18 and 19 and through said brushes to the selected 25 private branch exchange trunk. The calling subscriber's line is thus connected to the private branch exchange, and connection with a subscriber's telephone set at that exchange can be made in any usual or suitable manner. When the subscriber calling the old number hangs up his telephone the relay 6 is de-energized and closes its back contact 7 thereby completing a circuit for release magnet 23 as follows: from ground 30 battery, through release magnet 23, off-normal contact 22, closed in the operated position of switch D, contact 7, to ground. The special switch D is thus restored to normal. Means are provided whereby if 35 all the private branch exchange trunks are busy, a busy tone is sent back to the calling subscriber. In such case the brushes, having tested the trunk terminals and having found them all busy, move a step farther 40 so that brush 18 is connected with the busy tone apparatus 24. It is obvious that if a subscriber, instead of having had a single old number, had had two or more numbers, he can still be reached by calling any one 45 of the old numbers by merely duplicating the special switches D and extending each of the trunks 1, 2, 3, to terminals on each of the switches D. In such case the conductors 25 would extend to the terminals 50 of one of such additional switches D and the pair of conductors 26 to the terminals of still another such switch. The special switch D, is preferably provided with an additional side switch arm 27, arranged in 55 its second position to close a circuit for an electromagnet 28. Each time the magnet 28 is energized it attracts its armature 29 and actuates a ratchet 30 of a register wheel 31. The register thus makes one count each time 60 the switch D is used. By thus indicating

how frequently the old number is called, it can be determined when the new number has been generally adopted by the other subscribers of the system; and hence when the use of the special switch may be discontinued. 70

What is claimed is:

1. In a telephone system, terminals representing a subscriber's old number, terminals representing said subscriber's new number, a line connecting said new number terminals to the subscriber's station, and an automatically operating switch for extending a connection from said old number terminals to said line. 75
2. In a telephone system, terminals representing a subscriber's old number, terminals representing said subscriber's new number, a line connecting said new number terminals to the subscriber's station, and an automatic switch connected to said old number terminals and having terminals connected to said line. 80
3. In a telephone system, terminals representing a subscriber's new number, private branch exchange trunks connected to said terminals, terminals representing said subscriber's old number, and an automatic trunk-hunting switch connected to said old number terminals and having terminals connected to 85 said line, which said private branch exchange trunks are connected. 90
4. In an automatic telephone exchange system, a connector having multiple terminals representing a subscriber's old number, a connector having multiple terminals representing said subscriber's new number, a line connecting said new number terminal to the subscriber's station, and an automatic switch connected to said old number terminals and having terminals connected to said line. 100
5. In an automatic telephone exchange system, a connector having multiple terminals representing a subscriber's old, discontinued, individual line number, connectors having multiple terminals representing said subscriber's new numbers, private branch exchange trunks connected to said connectors, and an automatic trunk-hunting switch connected to said old number terminals and having terminals to which said private branch exchange trunks are connected. 110
6. In a telephone system, terminals representing subscribers' new number, private branch exchange trunks connected to said terminals, terminals representing said subscriber's old number, a hunting switch for extending a connection from said old number terminals to terminals of an idle one of said trunks, and a register responsive to the operation of said switch. 115
7. In a telephone system, a telephone line, means including automatic switches for extending a connection to said line, terminals 120

at said switches representing different line numbers of said line, said telephone line being connected to certain of said terminals, and an electrically controlled switching device for joining other terminals to said telephone line.

In witness whereof, I hereunto subscribe

my name this 11th day of December A. D., 1914.

CHARLES L. GOODRUM.
